UNITED STATES PATENT OFFICE.

ISAAC HALL, OF BOSTON, MASSACHUSETTS.

LASTING-JACK.

SPECIFICATION forming part of Letters Patent No. 251,714, dated January 3, 1882.

Application filed June 4, 1881. (No model.)

To all whom it may concern:

Be it known that I, ISAAC HALL, of Boston, county of Suffolk, State of Massachusetts, have invented an Improvement in Lasting-Jacks, of 5 which the following description, in connection with the accompanying drawings, is a specification.

My invention relates to jacks for holding boots and shoes while an outer sole is being 10 nailed thereon or other work is being done to the bottom thereof; and it consists in the combination, with a metal last or metal-shod last provided with a recess in its top, of a standard or upright and locking-block connected therewith, adapted to enter the said recess when the said block is in the proper position, and then by an automatic movement of the said block to lock the last rigidly upon the said standard while the boot or shoe is being 15 operated upon. The said socket or recess in the last, as shown, is made straight at its rear side or toward the heel of the last, while its front side inclines first backward and then forward, forming an angular projection in the recess, 20 which is thus made narrower at the middle of its depth than at its mouth or at its deepest part. The standard at its rear side corresponds to the shape of the rear side of the said socket, while at its front side it inclines back, 25 forming a surface corresponding to the portion of the front edge of the socket, which inclines back from its mouth to the middle of its depth. The extremity of the front portion of the standard is recessed or cut away, and a wedge-shaped block is placed in the said recess, the 30 block being mounted on a rod extending through the said standard, and being movable longitudinally therewith toward and from the end of the said standard. A spring acts to 35 hold the said block down upon the end of the standard, the front face of the block inclining forward from its junction with the rearwardly inclined upper end of the front face of the standard, as shown in Fig. 2. The last can be placed 40 on the standard only when the rod and block are pressed upward above the standard by the action of a suitable lever or treadle. When the 45 block and last are allowed to descend together upon the top of the standard the said standard and block fill and fit the said socket, locking the last firmly in position. When it is desired

to remove the last the block is forced upward by means of the rod upon which it is mounted, and the last is thus partially raised from the standard and released from the wedging action between the front face of the block and the rear face of the standard, so that it can be 55 readily removed.

Figure 1 is a side elevation of my improved jack, the locking-block being elevated to permit the last to be mounted on or removed from the standard, as desired, the last being shown partly in section; Fig. 2, a similar view, with the locking-block lowered and the last fastened thereby upon the standard. Fig. 3 is an enlarged sectional detail of part of the last and last-block, and means to adjust and lock the same in position; Fig. 4, a detail of the key, 60 and Fig. 5 a detail of the block-adjusting device.

The metal last *a* is provided with a socket, *e*, extending inward from the top of the heel portion. The rear portion or wall of the said socket has its face 2 inclined preferably forward from the mouth or opening to the bottom of the said socket, as shown, and its front face inclined backward, as shown at 3, from the mouth to about the middle of the depth of the socket, and then inclined forward again, as shown at 4, to the bottom of the socket, which is thus 65 narrower from front to back at the middle of its depth than at its bottom or its mouth.

The standard *d*, mounted on the bench *e*, has at its upper end a notch or recess, 5, to receive the last-locking block *i*, which is mounted on a 70 rod, *m*, extended down through the said standard. The rod *m* and connected block *i* are normally pressed downward by a spring, *n*, thus retaining the said block in the recess at the top of the standard, the shape of the said end, together with the block *i* thereon, as shown in 75 Fig. 2, corresponding exactly to the shape of the socket in the last, the upper end of the said standard and block being dovetail-shaped, or wider than the said standard at the bottom of the said block, so that while in the position shown in Fig. 2 it is impossible to remove the last therefrom.

A lever, *r*, engaging the lower end of the rod *m*, is connected with and operated by a treadle, 80 *t*, to raise the said rod and remove the last-locking block *i* from its recess 5 at the end of the 85

standard *d*, as shown in Fig. 1, when a last may be readily placed thereon or removed therefrom, as shown in Fig. 1.

In order to place the last *a* upon the standard *d* and the treadle *t* is moved by the operator to raise the block *i*, as shown in Fig. 1, when the last *a* is properly placed thereon, it receiving the block *i* in the bottom and forward portion of the socket *c*, where it rests against the inclined face 4 thereof, after which the treadle is released and the last and block carried down together upon the standard, which wedges into the said socket, holding the said last rigidly. The last, when pressed upon from above, bears mainly with its surfaces 23 upon the rigid inclined portions of the standard at front and back, the block *i* merely serving to hold it securely in place thereon. When desired to remove the last the treadle *t* is depressed, thus raising the block *i*, causing it to act as a lifter and lift the last, and, if desired, throw it upward off from the standard.

The lower portion of the standard, above the bench *e*, may be made tubular in any usual way for the passage below the bench of the usual endless strap, (not shown,) which in practice will be passed over the sole on the boot or shoe, and will be pressed or held thereon by a treadle or the foot of the operator.

30 The last-block *b*, preferably of wood, has at its front end a pin, *g*, to enter a hole in the metal toe part of the last *a*, while at its rear end it is bored to receive a locking device composed of a pin, *o*, acted upon at one end by a spring, *f*, confined in a recess in the last, the spring being held therein by a plug, *g*. The tendency of the spring *f* is to throw the pin *o* far enough for its point to enter a hole in the block-adjusting device *h*, as in dotted lines, 35 which so locks the block that it cannot be removed from the last. The shank of the pin *o* is toothed, as at 8, to be acted upon by the toothed part 9 of the mover or key 10 of the block-locking device. This mover or key may be inserted into a hole in the last-block, so as to engage the toothed or notched part of the pin *o*; and then, by turning the shank of the key from its dotted-line position toward its full-line position, Fig. 3, the pin *o* will be 40 withdrawn from the last-block-adjusting de-

vice, and the block may then be easily lifted from the last *a*. This block-adjusting device *h* is shown as a screw having an enlarged beveled head provided with a hole or opening, 13, to receive the end of the pin *o*. By rotating 55 this adjusting device *h* its top may be moved more or less from the bottom of the last, so as to hold the large end of the block *b* more or less from the body of the last *a*, thus making the last more or less thick at its shank or in-step portion. 60

I claim—

1. The jack consisting of a last provided with a socket, and a standard therefor provided with a movable last-locking device or block to enable it to enter the said socket and lock the last rigidly thereon, substantially as described. 65

2. The standard and wedge-shaped locking-block fitted in a recess in the end thereof, and its spring-pressed actuating-rod to move the 70 said block, combined with the last provided with a socket shaped to fit the end of the standard and block when the latter is in position in the said recess, substantially as described. 75

3. The socketed last, combined with the standard and block *i*, and means, substantially as described, to move it longitudinally from the said standard, to thereby elevate and release the last or throw it from the standard, as hereinbefore set forth. 80

4. The combination, with the last *a* and its block *b*, of the spring-actuated toothed or notched pin and the key to withdraw the said pin, substantially as described. 85

5. The last *a* and its block *b*, combined with the block-adjusting device provided with a shank, which is inserted into the last between it and the block, substantially as described.

6. The last, its block, and adjusting device, 90 combined with the locking device to engage the said adjusting device, substantially as described.

In testimony whereof I have signed my name to this specification in the presence of two subscribers. 95

ISAAC HALL.
